By his Attorneys,

Elias H. Doane, Inventor

UNITED STATES PATENT OFFICE.

ELIAS HOWES DOANE, OF TONICA, ILLINOIS.

TRACK FOR DOOR-HANGERS.

SPECIFICATION forming part of Letters Patent No. 651,751, dated June 12, 1900.

Application filed October 19, 1899. Serial No. 734,074. (No model.)

To all whom it may concern:

Be it known that I, ELIAS HOWES DOANE, a citizen of the United States, residing at Tonica, in the county of La Salle and State of Illinois, have invented a new and useful Track for Door-Hangers, of which the following is a specification.

This invention relates to door-hangers, and has for its object to provide an improved track for supporting the door. It is further designed to provide improved means for conveniently securing the track to the wall of a building, so as to maintain the track in rigid condition and prevent sagging thereof, and also to provide improved stops for limiting the movement of the door in opposite directions, and finally to provide adjustable fastening devices, whereby the track may be accommodated to walls which are uneven on account of warped or shrunken boards.

To these ends the present invention consists in the combination and arrangement of parts, as will be hereinafter more fully described, shown in the accompanying drawings, and particularly pointed out in the appended claims, it being understood that changes in the form, proportion, size and minor details may be made within the scope of the appended claims without departing from the spirit or sacrificing any of the advantages of the invention.

In the drawings, Figure 1 is a perspective view of a door-hanger track constructed in accordance with the present invention. Fig. 2 is a transverse sectional view taken vertically through one of the fastenings which support the track and showing a door suspended from the track. Fig. 3 is a horizontal sectional view illustrating the manner of adjusting the track to a shrunken or warped wall. Fig. 4 is a front elevation of one end of the track, having a door suspended therefrom and showing the improved stop for limiting the movement of the door.

Corresponding parts in the several figures of the drawings are designated by like characters of reference.

Referring to the drawings, 1 designates the wall of a building, to which the track 2 is secured by means of the present invention. The track consists of a continuous straight

rail or strip of metal, disposed edgewise, and connected at a plurality of points to the wall by means of the fastenings 3. Each of these fastenings comprises a straight screw-threaded shank, which is driven into the outer side of the wall and has its outer end passing loosely through a suitable opening formed substantially midway between the upper and lower edges of the track. Provided upon the threaded portion of the shank is a pair of clamping-nuts 4 and 5, respectively, between which the track is clamped, and thereby fixedly connected to the fastening.

To brace each fastening there is provided a hanger 6, formed from a single length of strap metal or of a single casting, having its upper end provided with an attaching-ear 7 for the reception of a screw or other fastening 8, whereby the hanger is secured to the wall at a point above the track. The intermediate body portion of the hanger inclines outwardly and downwardly to the track and is provided with a pendent foot 9, having a transverse opening loosely receiving the outer end of the shank 3 and clamped between the inner nut 4 and the adjacent inner side of the track.

As clearly shown in Fig. 1 of the drawings, the track is located over the doorway 10 of a building and extends a suitable distance at one side thereof to accommodate the door in its open position and is secured intermediate of its ends by means of a plurality of these fastening devices. It will thus be apparent that the track may be readily put up, as the rail is originally provided with openings for the reception of the fastenings 3, and after the rail has been fitted to the fastenings the clamping-nuts are tightened against the rail.

By reference to Figs. 1 and 4 it will be noted that the respective end hangers 11 at each end of the track have their pendent feet 9 located against the outer side of the track, whereby the inclined portion of the hanger extends transversely across the upper edge of the track upon which the wheel 12 of the door-hanger 13 travels. Thus it will be apparent that the said wheel will come into contact with the inclined body of the hanger 6, which latter therefore forms a stop to limit the movement of the door 14.

The track is adapted to that class of sliding doors commonly provided with single-wheel hangers located at or near the respective opposite edges of the door, so that each wheel will be stopped by the respective end hanger, and thereby limit the movement of the door in opposite directions.

5 The means for accommodating or adjusting the track to a warped or shrunken wall has been shown in Fig. 3, in which the wall 1 presents an uneven surface, and to maintain the rail in a straight line it becomes necessary to set some of the fastenings 3 farther into the wall. This is accomplished by reason of the 10 fastenings passing loosely through the respective openings in the rail and also by the provision of the nuts 4 and 5 at opposite sides of the rail, as will be understood.

15 Having thus described the invention, what is claimed, and desired to be secured by Letters Patent, is—

20 1. A track for sliding doors and the like, comprising a rail, and fastening devices comprising hangers, the end hangers extending 25 across the upper edge of the rail, forming stops to limit the movement of the door in op-

posite directions, substantially as shown and described.

2. A track for sliding doors and the like, comprising a rail having a plurality of openings formed therethrough, screw-threaded fastenings passing loosely through the respective openings, upwardly-inclined hangers, having pendent feet loosely receiving the respective fastenings, and attaching ears at the 30 upper ends thereof, the feet of the intermediate hangers being located against the inner side of the rail, and the feet of the end hangers being located against the outer side of the rail, the body of said latter hangers extending 35 transversely across the upper edge of the rail, and clamping-nuts located at opposite sides of the rail, and clamping the latter to the hangers, substantially as shown and described.

40 In testimony that I claim the foregoing as my own I have hereto affixed my signature in the presence of two witnesses.

45 ELIAS HOWES DOANE.
